TURBINE ADJUTAGE

Anthony George Maldon Michell, Melbourne,
Victoria, Australia

Application April 9, 1948, Serial No. 19,989

5 Claims. (Cl. 253—22)

1

This invention relates to adjutages for the nozzles of water turbines of the class in which the inflow takes place in radial planes at the circumference of the turbine wheel. A turbine of this class has been described in the applicant's expired Patent No. 760,898, dated May 24, 1904.

In many cases in which water turbines are used, particularly in small installations, it is necessary, in order to enable a demand for power to be immediately met at any time, to keep a turbine unit running throughout the night and at other hours when little or no power is normally required. It is consequently important, in such cases, that the efficiency of the turbine-adjutage shall be as high as possible when producing no useful power, or only a small amount of power, as well as when operating at, or more nearly at, its full capacity. This feature of design is especially important when the total water supply is limited and is conserved by storage. The turbine adjutage which is the subject of the present invention has been designed to meet such conditions.

In the accompanying drawings, Fig. 1 is a longitudinal section of an adjutage constructed according to the invention, and shows also a segment of the turbine-wheel in external view. In this view the adjutage is closed.

Fig. 2 is a longitudinal section of the adjutage taken on a plane at right angles to Fig. 1 on the line II—II of the latter figure.

Figs. 3 and 4 are longitudinal sections taken on the same plane as Fig. 1, the adjutage being shown partially open in Fig. 3 and almost fully open in Fig. 4.

Fig. 5 is a cross-section of the adjutage on a plane through the line V—V in Fig. 1.

In Fig. 1 the turbine wheel 1, and the nozzle 2, with the adjutage, which consists essentially of the shell 3 and tongue 4, are shown in their correct positions for operation, but with the tongue 4 in the position in which it closes the adjutage. The shell 3 is attached to the nozzle 2 by screws 5 5a, which fasten lugs 6, 6a of the shell to lugs 7, 7a of the nozzle. The mutually meeting surfaces of the shell and nozzle are portions of cylindrical surfaces of accurately equal radii, so that when the parts are secured together the joint between them is water-tight. The interior surfaces 9, 9a of the shell 3 are plane and parallel, and its surfaces 10, 10a conform approximately, but with necessary working clearances, to the periphery of the wheel 1.

The tongue 4 has parallel plane sides by which it fits accurately, with a small working clearance,

2

between the plane surfaces 9, 9a of the shell 3; it is rotatably mounted in the shell by means of the spindle 11, whose axis is the line 8, 8. The spindle 11 is non-rotatably fixed in the tongue 4, as by key 11a, but is rotatably mounted in the shell 3, as by anti-friction bearings 12, 12a, Fig. 2. An arm 13 is rigidly attached to the spindle 11 at one of its ends, as by key 14.

The surface 4a of the tongue 4, at its end remote from the spindle 11, is accurately turned to a cylindrical form with axis 8, 8, (which is also the axis of the corresponding cylindrical surface of the shell 3), but with a slightly smaller radius than the latter, so that it has only a small and practically water-tight clearance from the cylindrical surface of the nozzle 2 to which it is opposed.

The surface 4b of the tongue 4, is shaped to conform approximately to the periphery of the wheel 1, with a small clearance, when the tongue is in the closed position shown in Fig. 1. It will be seen that the two surfaces 4a and 4b intersect one another approximately at a right angle. On its side remote from the wheel the surface of the tongue is also curved, and a space is provided in the interior of the shell 3 sufficiently large to allow the tongue to be rotated about the axis 8, 8 into the positions shown in Figs. 3 and 4. To prevent the tongue being rotated too far in the opposite direction, so as to bring it into contact with the periphery of the wheel, a pin 15 is passed through holes drilled in the side-surfaces 9, 9a of the shell 3 and through an arcuate slot 4c in the tongue of such circumferential length as to limit the motion of the tongue to the extent required.

35 A flexible strap 16 is attached to the curved rear surface of the tongue 4, by screw 17, as shown in Fig. 1, and a tension is maintained in this strap by a tension-spring 18 attached to the nozzle, as by a clevis 19, so tending always to 40 rotate the tongue about the axis 8, 8 towards the position shown in Fig. 1; in other words, to close the adjutage.

In operation, when the tongue 4 is rotated from the closed position of Fig. 1 (as by a governor-45 mechanism of any known construction acting on the arm 13), into a position, such as that shown in Fig. 3, a small jet of water is allowed to flow between the lower lip of the nozzle 2 and the angle of the tongue formed by the intersection of its surfaces 4a and 4b. This jet of water 50 20, springs clear of the outer surface 4b of the tongue and enters the wheel directly as a free jet without encountering any frictional resistance from such surface. When however by further 55 rotation, in the same direction, of the arm 13 and

tongue 4, the adjutage is opened to an extent approaching to that of full power, as shown in Fig. 4, the issuing stream of water strikes the surface 4b of the tongue which then serves to guide and direct the increased stream 20a into the wheel 1.

The stream 20a is then subjected to fluid friction by its contact with the surface 4b of the tongue but, being relatively large, only a small fraction of its energy is absorbed thereby. When 10 the stream is small, on the other hand, as shown at 20, Fig. 3, contact over the surface 4b, if allowed to occur, would absorb a large portion of its energy.

I claim:

1. A nozzle for a water turbine, the outflow end of said nozzle being terminated by an arc of a concave cylindrical surface and being constructed to form an aperture of fixed dimension through said surface, combined with an adjutage comprising plane parallel sides, a tongue between said sides pivotally supported near one of its ends on an axis spaced from said surface of the nozzle, its other end being terminated by an arc of a convex cylindrical surface of the same radius as that of the end of the nozzle, opposed to, matching and movable over the apertured end of the nozzle to form therewith an adjustable valve.

2. A nozzle for a water turbine, the outflow end of said nozzle being terminated by an arc of a concave cylindrical surface and being constructed to form an aperture of fixed dimension through said surface, combined with an adjutage comprising plane parallel sides, a tongue between said sides pivotally supported near one of its ends on an axis spaced from said surface of the nozzle, its other end being terminated by an arc of a convex cylindrical surface of the same radius as that of the end of the nozzle, opposed to, matching and movable over the apertured end of the nozzle to form therewith an adjustable valve, the pivotally supported end of the tongue forming a transverse edge of the outflow end of the adjutage, said tongue having a liquid guiding surface interconnecting its arcuate end surface and said outflow edge.

3. A nozzle for a water turbine, the outflow end of said nozzle being terminated by an arc of a concave cylindrical surface and being constructed to form an aperture of fixed dimension through said surface, combined with an adjutage comprising plane parallel sides, a tongue between said sides pivotally supported near one of its ends on an axis spaced from said surface of the

5 nozzle, its other end being terminated by an arc of a convex cylindrical surface of the same as that of the end of the nozzle, opposed to, matching and movable over the apertured end of the nozzle to form therewith an adjustable valve, the pivotally supported end of the tongue forming a transverse edge of the outflow end of the adjutage, said tongue having a curved liquid guiding surface intersecting the apertured end surface of the nozzle, interconnecting its arcuate end surface and said outflow edge.

15 4. A nozzle for a water turbine, the outflow end of said nozzle being terminated by an arc of a concave cylindrical surface and being constructed to form an aperture of fixed dimension through said surface, combined with an adjutage comprising plane parallel sides, a tongue between said sides pivotally supported near one of its ends on an axis spaced from said surface of the nozzle, its other end being terminated by an arc of a convex cylindrical surface of the same radius as that of the end of the nozzle, opposed to, matching and movable over the apertured end of the nozzle to form therewith an adjustable shut-off valve, the pivotally supported end of the tongue forming a transverse edge of fixed position of the outflow end of the adjutage, said tongue having a curved liquid guiding surface intersecting the apertured end surface of the nozzle at substantially right angles, interconnecting its arcuate end surface and its outflow edge.

20 5. In combination with a water turbine wheel, a nozzle therefor constructed to form an aperture of fixed dimension, an adjutage having a shell affixed to the nozzle having plane parallel walls disposed on opposite sides of the nozzle aperture and extending from the end of the nozzle over the turbine wheel, a movable tongue having flat sides fitting said walls and pivoted thereto near one of its ends on an axis spaced from the end of the nozzle, the other end of the tongue extending to the nozzle to form with the aperture thereof an adjustable shut-off valve, the side of the shell adjacent the turbine wheel being open.
